PAGE 3

FIG. 5

FIG. 6

FIG. 7

FIG. 8

FIG. 1 is a perspective view of a pushbutton telephone deskstand, showing one form of my new design with flat topped pushbuttons;

FIG. 2 is a top plan view of the form shown in FIG. 1;

FIG. 3 is an enlarged partial cross-sectional view of the face plate of the pushbutton telephone deskstand shown in FIG. 1, taken along the line 3—3 of FIG. 2;

FIG. 4 is a side elevational view of the form shown in FIG. 1, the opposite side having substantially the same appearance;

FIG. 5 is a perspective view of a pushbutton telephone deskstand showing another form of my new design with concave-topped pushbuttons and collars disposed about the pushbuttons;

FIG. 6 is a top plan view of the form shown in FIG. 5;

FIG. 7 is an enlarged partial cross-sectional view of the face plate of the pushbutton telephone deskstand shown in FIG. 5, taken along the line 7—7 of FIG. 6; and

FIG. 8 is a side elevational view of the form shown in FIG. 5, the opposite side having substantially the same appearance.

This application is a continuation-in-part of my application, Serial No. D. 68,598, filed January 31, 1962, abandoned subsequent to filing this application.

The broken line showing of legible matter is for illustrative purposes only.

I claim:

The ornamental design for a pushbutton telephone deskstand, substantially as shown and described.
